(57) **CLAIM**

The ornamental design for a peg board hook, as shown and described.

DESCRIPTION

FIG. 1 is a perspective view of a peg board hook showing my new design.

FIG. 2 is a side elevational view thereof.

FIG. 3 is a side elevational view of a side opposite that shown in FIG. 2.

FIG. 4 is a top plan view thereof.

FIG. 5 is a bottom plan view thereof.

FIG. 6 is a front elevational view thereof; and,

FIG. 7 is a rear elevational view thereof.

The broken lines represent environment and form no part of the claim. The boundary lines represent boundaries of the claim and form no part of the claim.
